US00D703547S

(12) **United States Design Patent**
France et al.

(10) **Patent No.:** **US D703,547 S**
(45) **Date of Patent:** **** Apr. 29, 2014**

(54) **MICROWAVABLE BAG**

(75) Inventors: **David W. France**, Omaha, NE (US);
Clifton Lachmansingh, South Haven, MN (US)

2,673,805 A 3/1954 Colman
2,673,806 A 3/1954 Colman
2,740,576 A 4/1956 Franck
2,741,559 A 4/1956 Banowitz
2,815,164 A 12/1957 Painter

(Continued)

(73) Assignee: **ConAgra Foods RDM, Inc.**, Omaha, NE (US)

FOREIGN PATENT DOCUMENTS

(**) Term: **14 Years**

DE 1786047 11/1972
DK 81544 12/1956

(21) Appl. No.: **29/394,183**

(Continued)

(22) Filed: **Jun. 14, 2011**

OTHER PUBLICATIONS

(51) LOC (10) Cl. **09-05**

U.S. Official Action mailed Feb. 23, 2012, in U.S. Appl. No. 11/970,349.

(52) U.S. Cl.

FIG. 1 is a perspective view of a microwavable bag.

FIG. 2 is top plan view thereof.

FIG. 3 is front elevation view thereof.

FIG. 4 is a right side elevation view thereof.

FIG. 5 is a rear elevation view thereof.

FIG. 6 is a left side elevation view thereof; and,

FIG. 7 is a bottom plan view thereof.

Portions of FIGS. 1 through 7 are shown in broken lines. The broken lines illustrate portions of the microwavable bag that form no part of the claimed design.

1 Claim, 7 Drawing Sheets
